ATTORNEYS

UNITED STATES PATENT OFFICE.

CARL P. BOHLAND, OF ST. PAUL, MINNESOTA.

WASHING-BOWL.

1,393,925.

Specification of Letters Patent. Patented Dec. 13, 1921.

Application filed April 5, 1920. Serial No. 371,215.

To all whom it may concern:

Be it known that I, CARL P. BOHLAND, a citizen of the United States, residing at St. Paul, in the county of Ramsey and State of Minnesota, have invented a new and useful 5 Washing-Bowl, of which the following is a specification.

This invention relates to improvements in automobile washing bowls, the primary object being to provide improved means whereby accumulated mud, dirt, dust, etc. may be flushed from wheels, running gear and mud guards by driving the vehicle to be washed into, around and out of the bowl. With this 10 and other objects in view, my invention comprises the features of construction and combination of parts hereinafter more particularly described and claimed.

In the accompanying drawing forming 20 part of this specification, Figure 1 is a plan of my invention; Fig. 2 is a section taken on the line 2—2 of Fig. 1, showing a portion of my improved washing bowl; Fig. 3 is a central cross section taken on the line 3—3 of Fig. 1, and Fig. 4 is a section taken on the line 3—3 of Fig. 1, showing a detail of the drain and overflow ducts.

My invention comprises a shallow bowl forming a wide reservoir and having a floor 30 or bottom 10 and a side wall 11, said side wall in the construction illustrated being substantially of circular shape and the floor sloping downwardly toward the center of the structure. Where the vehicles enter and 35 leave the bowl, ramps 12 and 13 are provided with suitable grades, so that there will be no loss of water when vehicles are entering or leaving the bowl. This entire structure may be formed and constructed out of cementitious material, or out of any other suitable material desired. The bowl is equipped with a valve controlled water supply pipe 40 14, an overflow pipe 15, and a suitable settling basin 16 near the center of the structure, over which a removable grate 17 is placed. The duct 15 enters a drain pipe 15', said drain pipe being connected with the bottom of the bowl and opened and closed by a valve 21. The valves closing the supply pipe 50 and drain pipe are controlled respectively by the handle 18 and the handle 19, the latter being connected with its valve 21 by suitable valve gearing 20, drive rod 20', cam 20" and cam operated valve stem 20'''.

55 In use the vehicles entering the bowl to flush the mud and dirt from their wheels,

running gear, etc., are made to travel around in the bowl as often as is necessary to dissolve and flush off the dirt. The bottom of the bowl which slants toward the center gives 60 greater depth for emersion of the wheels and running gear near the center of the bowl. By slanting the floor of the bowl toward the center, the water will deposit all heavy material in the settling basin. Any silt or mud 65 adhering to the main area of the bowl can also be more easily flushed down into the settling basin with a stream of water from a hose. When the settling basin becomes 70 filled with silt, etc., the grate can be removed and the accumulated mud can be shoveled into a dump wagon and hauled away. The drain valve can be opened or closed from a distant point by use of the structure illustrated, thus enabling an attendant to control the operation of the drain valve without having to enter the bowl.

In accordance with the patent statutes, I have described the principles of operation of my invention, together with the apparatus 80 which I now consider to represent the best embodiment thereof, but I desire to have it understood that the construction shown is only illustrative, and that the invention can be carried out by other means and applied to 85 uses other than those set forth within the scope of the following claims.

Having described my invention what I claim as new and desire to protect by Letters Patent is:

1. In a device of the class described, a shallow receptacle for a washing fluid providing an endless submerged course for vehicles, said course sloping downwardly and inwardly to a central area, said area being depressed to form a settling basin, the inclination of said course serving to aid drivers in the management of their vehicles and also serving to direct silt accumulating from the vehicles toward the settling basin during the 100 agitation of the liquid by the moving vehicle.

2. In a device of the class described, a shallow receptacle for a washing fluid providing an endless submerged course for vehicles, said course sloping inwardly and downwardly to a central area, said area being depressed to form a settling basin and a drain duct located centrally within said settling basin and opening at the level of 110 the top thereof, whereby the fluid entering said duct first passes over the basin.

- 2
3. A device of the class described, comprising a shallow receptacle for a washing fluid, said receptacle providing an endless submerged course for vehicles, and spaced 5 entering and leaving ramps leading to and from the receptacle in tangential directions with respect to said course.
4. A device of the class described, comprising a shallow receptacle for a washing fluid, said receptacle providing an endless submerged course for vehicles and a ramp leading into the receptacle in a tangential direction with respect to said course.
5. A device of the class described, comprising a shallow receptacle for a washing fluid, said receptacle providing an endless submerged course for vehicles, and a ramp leading into said course at a relatively 10 small angle with respect thereto.
6. A device of the class described, comprising a shallow receptacle for a washing 15 fluid, a ramp leading into said receptacle, the bottom of the receptacle providing an endless, submerged, dished run-way for vehicles propelled therein. 25
7. In a device of the class described, a shallow receptacle for a washing fluid furnishing an endless submerged course for vehicles, a settling basin, said course being sloped toward said basin and a drain duct 30 leading from the receptacle and opening at a point above the bottom of said basin.
8. A device of the class described, comprising a shallow receptacle for a washing fluid having means of ingress and egress 35 for vehicles, the bottom of the receptacle providing a turning run-way dished to aid drivers in the management of their vehicles.

In testimony whereof, I have signed my name to this specification.

CARL P. BOHLAND.
